UNITED STATES PATENT OFFICE

GORDON FRASER, NORMAN FRASER, AND JOHN FRASER, OF ARBROATH, SCOTLAND

SLIVER-BALLING MACHINE

Application filed June 5, 1930, Serial No. 459,406, and in Great Britain June 17, 1929.

This invention relates to machines contrived to form rolls or balls of sliver or the like upon a sectional arbor or mandrel, being concerned more particularly with machines 5 for making and ejecting rolls of sliver delivered continuously from a card or drawing frame or other machine which delivers fibre in sliver or ribbon form.

For convenience we shall describe in detail 10 a machine adapted for handling the sliver from a card or drawing frame.

A machine constructed in accordance with the invention comprises a pair of axially spaced discs, revoluble arbors extending axially of said discs and normally having their ends contiguous, said arbors being retractible clear of the space between the discs, and a driven endless band (or chain) engageable with said arbors and serving, when sliver is 20 delivered to the arbors, to build a sliver roll thereupon and, finally, when the arbors are retracted, to eject the roll from between the discs.

Automatic means may be provided for separating the arbors and returning them to end to end position, as described in the specification of our prior application Serial No. 394,107 filed 20th September, 1929. Manually operable means may also be provided for 30 effecting ejection of a partially formed roll.

In the accompanying drawing Fig. 1 is a more or less diagrammatic side elevation of a sliver balling machine constructed in accordance with the invention and Fig. 2 a fragmentary detail view showing a modification.

The machine shown comprises a pair of axially spaced discs as 1 and extending axially thereof a pair of revoluble arbors as 2 which are normally contiguous but which 40 are retractible clear of the space between the discs 1.

3 denotes an endless band engageable with the arbors 2 and serving, when sliver 4 is delivered to the arbors, to build a sliver roll 4' thereupon and, finally, when the arbors 2 are retracted, to eject the roll from between the discs 1.

Each disc 1 is mounted for rotation on a horizontal axis on a hollow journal 5 carried 50 by a gable frame 6 disposed on the corre-

sponding side of the machine. The arbors 2, which extend, normally, through the journals 5, are revolubly mounted on the upper ends of a pair of levers 7 of which the lower ends are pivoted at 8 transversely of the axis 55 of the discs, the arrangement being such that the arbors 2 are retracted clear of the space defined between the discs 1 when the levers 7 are rocked on their pivots 8 to separate the upper ends of said levers. Disposed adjacent 60 to and around the periphery of the discs are three pulleys 9, 10 and 11, two of which, namely 9 and 10, have fixed axes and the other 11 of which constitutes a jockey pulley and has a movable axis. The pulleys 9—11 65 are wrapped by the endless band 3 of which the flight extending between the pulleys 9, 10 is movable within the space defined between the discs 1, so as frictionally to engage the arbors 2, or sliver wound on the arbors, 70 under the control of the jockey pulley 11. The jockey pulley 11 is conveniently carried on one arm 12 of a bell-crank lever 12, 13 pivoted at 14 and having adjustably mounted on its other arm 13 a counterweight 16 serving to load the lever in the direction to tension the band 3. 75

The pulley 10 constitutes a driver.

A slight clearance is left between the adjacent ends of the arbors 2 when in end to end 80 relation.

In operation, the sliver 4 from card delivery rolls indicated at 17, 18 is inserted between the arbors 2, and the bell-crank lever 12, 13 released, whereby the band 3 engages 85 and accelerates the arbors 2 and frictionally engages the sliver roll being built thereupon. When the sliver roll has attained a predetermined diameter, the arbors 2 are retracted, whereupon the stretched band 3 effects ejection 90 of the roll from between the discs 1, the arbors 2 being thereafter restored to position ready for a subsequent roll-forming operation. When necessary, in order to eject a partially formed roll, the bell-crank lever 12, 13 is manually operated to ease the driving-band pressure on the roll and arbors. The arbors are then retracted. Then by reverse movement of the lever the driving-band is 95 again stretched so as to cause ejection of the 100

roll, the arbors being then closed on the sliver to start another roll.

It will be understood that, during the roll-building operation, the band 3 supplies the requisite pressure to compact the roll. If necessary, each of the pulleys 9-11 may be divided as shown in Fig. 2 and the band 3 may be attached to a positively driven chain 19 engaged by a sprocket wheel 20 intermediate the pulley halves.

The discs 1 may be stationary when the roll starts building but will commence rotation as the roll increases in diameter.

What we claim is:—

1. A sliver balling machine comprising a pair of axially spaced discs, revoluble arbors extending axially of said discs and normally having their ends contiguous, said arbors being retractible clear of the space between said discs, and a driven endless member engageable with said arbors and serving, when sliver is delivered to said arbors, to build a sliver roll thereupon, and, when said arbors are retracted, to eject the roll from between said discs.

2. A sliver balling machine comprising a pair of axially spaced discs, a pair of levers pivoted at their lower ends on axes transverse to the axis of said discs, arbors revolubly mounted on the upper ends of said levers, said arbors extending axially of said discs and normally having their ends contiguous, said arbors being retractible clear of the space between said discs on rocking said levers apart, and a driven endless member engageable with said arbors and serving, when sliver is delivered to said arbors, to build a sliver roll thereupon, and, when said arbors are retracted, to eject the roll from between said discs.

3. A sliver balling machine comprising a pair of axially spaced discs, revoluble arbors extending axially of said discs and normally having their ends contiguous, a set of pulleys disposed adjacent to and around the periphery of said discs, two of said pulleys having fixed axes and a third pulley having a movable axis, and a driven endless band wrapping said pulleys, said band engageable with said arbors and serving, when sliver is delivered to said arbors, to build a sliver roll thereupon, and, when said arbors are retracted, to eject the roll from between said discs.

4. A sliver balling machine comprising a pair of axially spaced discs, revoluble arbors extending axially of said discs and normally having their ends contiguous, a set of three pulleys disposed adjacent to and around the periphery of said discs, two of said pulleys having fixed axes, a lever one arm of which carries the third pulley, the other arm of said lever being adjustably loaded, and a driven endless band wrapping said pulleys, said band engageable with said arbors and serving, when sliver is delivered to said arbors,

to build a sliver roll thereupon, and, when said arbors are retracted, to eject the roll from between said discs.

In testimony whereof we have signed our names to this specification.

GORDON FRASER.
NORMAN FRASER.
JOHN FRASER.
